COMPRESSOR

Win W. Paget, Michigan City, Ind., assignor to
Sullivan Machinery Company, a corporation
of Massachusetts

Continuation of application Serial No. 37,864,
August 26, 1935. This application April 27,
1940, Serial No. 332,125

4 Claims. (Cl. 230—58)

My invention relates to compressors, and more particularly to portable compressor outfits especially designed for use in mines.

An object of this invention is to provide an improved portable compressor outfit. Another object is to provide an improved portable compressor outfit of an extremely low, compact design especially adapted to use in "low vein" coal mines or other restricted locations. A further object is to provide an improved portable compressor outfit having the various elements thereof arranged in a novel manner whereby unusual compactness is attained. Another object is to provide an improved compressor cooling system. Still another object is to provide a novel cooling system for the compressor and air receiver of a compressor outfit of the above character. A further object is to provide a novel arrangement of the compressor element with respect to its driving motor and a novel manner of mounting the compressor element. Yet another object is to provide an improved air compressor outfit having a novel general arrangement of parts. These and other objects and advantages of the invention will, however, hereinafter more fully appear.

In the accompanying drawings, there is shown, for purposes of illustration, one form which the invention may assume in practice.

In these drawings—

Fig. 1 is a plan view of the illustrative form of the improved portable compressor outfit.

Fig. 2 is a side elevational view of the compressor outfit shown in Fig. 1.

Fig. 3 is a view in longitudinal section, taken substantially on line 3—3 of Fig. 1.

Fig. 4 is a cross sectional view with parts shown in end elevation, taken substantially on line 4—4 of Fig. 1.

In this illustrative embodiment of the invention there is shown a portable mine car compressor outfit of the "low vein" type generally comprising a portable base 1, supporting a driving motor 2, an air compressor 3 and an air receiver 4, and having a novel cooling arrangement, generally designated 5.

The portable base 1 is in the form of a truck frame 6 of open-center, rectangular form, having transverse supporting axles 7 extending beneath the elements supported by the truck frame and in turn supporting bearings at their projecting extremities for journaling car wheels 8 adapted to run along a mine trackway. These axles are preferably of rectangular cross section and mounted in suitable axle boxes 9 secured to the truck frame. Supported at the sides of the truck frame and projecting down within the open center thereof, with its axis lying in the longitudinal center of the compressor outfit, is the motor 2. This motor is herein preferably of the electric type, having its power shaft 10 horizon-

tally and longitudinally disposed in the manner shown in Fig. 3. The bottom portion of the casing of the motor is transversely recessed at 11 to receive the wheel axle underlying the motor. The compressor 3 is herein arranged in a compact manner between the air receiver 4 and the motor 2, and has its crank case 12 directly attached to the motor casing so that the compressor is solely supported by the motor. The compressor 3 is of the V-type, and its cylinders 13 project radially from the crank case 12, and the crankshaft 14 of the compressor is, in this instance, an integral continuation of the motor power shaft 10. It is accordingly evident that the motor and compressor form a compact unitary structure lending simplicity and ruggedness. The air receiver 4 is arranged in a low position at the end of the truck frame opposite from the motor, with its longitudinal axis in coincidence with the motor axis and the axis of the compressor crankshaft, and, in this instance, has integral side ledges 15 supported on the sides of the truck frame. The air receiver carries in coaxial relation therewith, and extending from the inner end thereof in the direction of the compressor, a cylindrical shell 16 which, as herein-after explained, constitutes an air-flow-directing element, and this shell surrounds, in part, the compressor and has a removable top 17 to permit access to the fan later described. The walls of the shell 16 at the inner end thereof are suitably recessed or notched as at 18" to clear the compressor cylinders and the adjacent truck wheel axle. As illustrated, the air receiver 4 is located in a low position within the open center of the truck frame and its bottom lies below the top of the adjacent truck wheel axle, at the outer side of the latter. The several frame-supported parts are mounted on rubber to reduce vibration and protect them from jars.

The air compressor 3 is of the air-cooled type, provided with the usual cooling fins, and the improved air-cooling system for the compressor is also adapted to aid in cooling the air receiver 4 and air discharge conduits. The means for accomplishing this double cooling function consists of a series of air flow openings 17 cut in the walls of the cylindrical shell 16 at the end thereof nearest the compressor, and the opposite end of the shell adjacent the receiver is perforated by air flow openings 18. The bulging end of the receiver at 4' adds to the cooling effect, aids in best cooling-air distribution, and reduces the tendency of the air streams to leave the walls of the receiver. Fixed to the projecting end of the compressor crankshaft 14, within the shell 16, and driven by the crankshaft, is an air circulating fan 19 for creating a flow of air through the shell, the air being drawn in through the flow openings 17 past the compressor cylinders, cooling the latter, and the air flowing past the

compressor cylinders is blown longitudinally through the shell against the adjacent end of the air receiver and laterally through the openings 18 past the exterior of the air receiver, to cool the latter.

The air compressor cylinders have air intake conduits 20, 20 each provided with a conventional form of air cleaner 21, and the air compressed within the cylinders is discharged out through discharge conduits 23, 23 to the air receiver 4, the conduits 23, 23 having usual heat-radiating fins and extending longitudinally near certain of the air discharge openings 18 in the flow-directing shell 16, so that some cooling effect of these discharge conduits is obtained.

As above mentioned, the truck wheel axles pass across the truck frame beneath the motor and air-directing shell, through transverse recesses above the bottoms of the motor and air receiver, and the motor and air receiver are supported in a low underslung position on the truck frame, so that minimum overall height is obtained. It will be evident that by the coaxial arrangement of the motor, air receiver and air-flow-directing shell, a straight-line top surface is obtained, while at the same time cooling is improved and longitudinal compactness made possible. Further, by the particular arrangement of the various elements on the base, the entire outfit is made extremely compact, not only vertically but also longitudinally and laterally, thereby enabling the outfit to operate in "low vein" mines having entries and stalls of relatively restricted dimensions. Further, by mounting the compressor directly on the motor casing and arranging the other related parts in the manner disclosed, the outfit is made not only relatively simple in design but also extremely rugged, well adapted to meet the severe conditions of service. It will also be evident that by forming the compressor crankshaft as an integral continuation of the motor power shaft, simplicity in structure is made possible, while efficiency is at the same time improved. These and other advantages of the improved compressor design will be obvious to those skilled in the art.

This application is a continuation of my application Serial No. 37,864, filed August 26, 1935.

While there is in this application specifically described one form which the invention may assume in practice, it will be understood that this form is shown for purposes of illustration and that the invention may be modified and embodied in various other forms without departing from its spirit or the scope of the appended claims.

What I claim as new and desire to secure by Letters Patent is:

1. In a compressor apparatus, a base, a receiver on said base, a multi-cylinder compressor on said base alined with said receiver, a fan driven with said compressor and between the same and said receiver, said receiver having a bulging end extending towards said fan, and air flow guiding and directing means comprising a shell constituting a substantial extension of the receiver walls, and circumferentially ported near the end of the receiver nearer the fan and having its other end notched to receive the compressor cylinders.

2. In a compressor apparatus, a base, a receiver on said base, an air-cooled compressor on said base, said receiver having an end facing towards said compressor and said compressor

having cylinders extending towards the opposite sides of said base and a crankshaft extending longitudinally of the base and parallel to a line parallel to the center line of said receiver, a fan driven with said compressor and arranged between the same and said receiver, and air flow guiding and directing means comprising means forming a wall constituting a substantial extension of the top wall of the receiver and overlying the adjacent ends of the cylinders and other walls formed to provide openings through which the compressor cylinders extend laterally outwardly, said wall forming means providing other openings in a transverse zone between the receiver and the compressor whereby cooling air flow may be effected by said fan transversely relative to the end of the receiver and, in a direction longitudinal of the apparatus, also transversely relative to the compressor cylinders.

3. In a compressor apparatus, a base, a receiver on said base, an air cooled multi-cylinder compressor on said base alined with said receiver and having cylinders extending towards the opposite sides of said base, a motor on said base for driving said compressor, a fan driven with said compressor and arranged between said compressor and said receiver, air flow guiding and directing means comprising a cylindric shell constituting a substantial extension of the outer walls of said receiver and extending between said compressor cylinders above the adjacent ends of the latter, said shell having openings to receive the compressor cylinders and other openings near the adjacent end of said receiver whereby cooling air flow may be effected by said fan relative to said receiver and, in a direction longitudinal of the apparatus, also relative to said compressor cylinders, and discharge conduits for conducting compressed fluid from said cylinders to said receiver and extending longitudinally of the apparatus along the sides of the receiver, said conduits disposed near certain of said last mentioned openings whereby cooling air passes over said conduits.

4. In a compressor apparatus, a base, a receiver on said base near one end thereof, a motor on said base near the opposite end thereof for driving a compressor, an air cooled compressor on said base between said motor and said receiver, 50 said receiver and motor having their adjacent ends facing towards said compressor and said compressor having cylinders extending towards the opposite sides of said base and a crankshaft extending longitudinally of the base and parallel to a line parallel to the center lines of said receiver and said motor, a fan driven with said compressor and arranged between said compressor and said receiver, and a cylindric air flow guiding and directing shell having its walls constituting a substantial extension of the walls of said receiver and said motor and within which said fan is arranged, the walls of said shell formed to provide openings through which the compressor cylinders extend laterally outwardly and also formed to provide other openings in a transverse zone between the receiver and the compressor and in a transverse zone between said motor and the compressor whereby cooling air flow may be effected by said fan transversely relative to the adjacent ends of said receiver and said motor and, in a direction longitudinal of the apparatus, also transversely relative to the compressor cylinders.
